UNITED STATES PATENT OFFICE

CARL P. BROCKWAY, OF PATERSON, NEW JERSEY, ASSIGNOR TO INDUSTRIAL RESEARCH CORPORATION, OF TOLEDO, OHIO, A CORPORATION OF DELAWARE

VACUUM SWEEPER

Application filed January 23, 1919, Serial No. 272,728. Renewed May 14, 1927.

This invention relates to improvements in suction sweepers and particularly to improvements upon my co-pending, simultaneously filed application, Serial Number 5 272,727.

The principal object of the invention is to obtain an efficient sweeping of carpets and other fabrics, particularly those having long nap. The usual suction nozzle in passing 10 over a carpet for instance, as it approaches a given thread will attract the thread and bend it backward, the thread following the suction to a vertical position as the nozzle moves directly above it, and then bending forward 15 as the nozzle moves away. Each thread therefore receives but one complete oscillation. With a strong suction this movement would probably be sufficient to effect a satisfactory cleaning of the carpet were it not 20 for the fact that threads behind the line of strongest suction are drawn forward at the same time that threads in advance of the line are drawn backward, thus producing together at their outer ends a more or less effective barrier to the action of the suction 25 upon dust particles embedded lower down in the carpet. It is the object of my invention to produce a constant oscillation backward and forward, or otherwise, of the line or 30 point of strongest suction, thus overcoming the difficulties just mentioned, and also causing the threads of the fabric to vibrate more or less rapidly, thereby loosening and dislodging the dust particles.

Another object of the invention is the provision of means for moving the air inlet with respect to the machine as a whole without moving the nozzle.

A further object of the invention is the provision of means for driving the inlet moving means from the revolving fan employed to produce the suction.

Other objects, and objects relating to details of construction, and economies of manufacture will appear as I proceed with the description of that embodiment of my invention, which for the purposes of the present application I have illustrated in the accompanying drawing, in which:

Figure I is a top plan view of a suction sweeper embodying my invention.

Fig. II is a longitudinal section taken approximately on the line II—II Fig. I.

Fig. III is a bottom plan view of the machine.

Fig. IV is a vertical cross-section through the nozzle and oscillating shutter taken substantially on the line IV—IV Fig. II.

Fig. V is a vertical cross section taken substantially on line V—V Fig. II.

Similar reference characters refer to similar parts throughout the views.

In the drawing, 10 represents the fan of the suction cleaner driven by an electric 65 motor 11, exhausting into a dust collecting bag 12, a fragment only of which is shown in the drawing.

An air tight casing 13 surrounds the fan and is provided with a forwardly extending 70 portion 14 constituting a chamber or passage through which air may enter the fan casing proper. The casing merges at its forward end into a nozzle 15 having on its lower side a mouth 16 arranged to lie in close proximity 75 to the surface over which the machine is moved. The machine is supported upon traction wheels 17 mounted on an axle 18 positioned in brackets 19 secured to the bottom of the casing and upon a caster 20 mounted 80 on the rear of the motor casing at the middle.

In the side or end walls of the nozzle there are located machine screws 21 which at their ends extending into the nozzle chamber are turned down to form smooth pintles. Upon 85 these pintles there is pivoted a closure or shutter consisting of a shutter plate 22, spider arms 23 and rock shaft 24. The shutter plate 22 is provided with an opening here illustrated as a slot 9 extending entirely across 90 the shutter.

Fixed upon the rock shaft 24 is a small crank arm 25 to which motion is imparted by a connecting rod 26. The latter is driven by a crank shaft 27 mounted in the side walls of 95 the casing. The crank portion of the shaft 27 is indicated at 28 in Fig. II of the drawing. Upon the shaft 27 is fixed a worm gear 29 which is driven by a worm 30 mounted upon a shaft 31, the forward end of which turns 100

in a bearing 32 secured to the casing and which preferably also constitutes the shaft for the fan 10 and the motor 11.

In the operation of my invention the machine is moved by means of any convenient handle, not shown. The motor when set in operation turns the fan 10 to create suction tending to cause air to move upwardly through the mouth 16 of the nozzle. Except for a small leakage around the sides of the shutter plate 22 this air must pass through the slot 9. The slot, however, is constantly oscillating backward and forward, causing a corresponding movement of the point or line of suction, which serves to agitate the threads of the fabric being cleaned, thereby loosening the dirt, and which also serves to reduce greatly the tendency of the threads to form a barrier against the action of the suction at its strongest point.

I am aware that the particular embodiment of my invention above described and illustrated in the accompanying drawings is susceptible of considerable variation without departing from the spirit thereof and therefore I desire to claim my invention broadly as well as specifically as indicated by the appended claims.

I claim as my invention:

1. In a suction sweeper, an air exhausting means, a nozzle, a chamber connecting said exhausting means and nozzle, a movable shutter extending across the mouth of said nozzle, said shutter having an air inlet opening therethrough and means to produce a rapid succession of movements of said shutter with respect to the nozzle.

2. In a suction sweeper, a high speed rotary exhausting means, a nozzle, a chamber connecting said exhausting means and nozzle, a movable shutter extending across the mouth of said nozzle, said shutter having an air inlet opening therethrough and speed reduction transmission mechanism intermediate said shutter and exhausting means operative to produce a succession of movements of said opening with respect to the mouth of the nozzle.

In testimony whereof, I affix my signature.

CARL P. BROCKWAY.
